FIG. 1 is a side elevational view of a dental mouth mirror showing my new design;

FIG. 2 is a plan view of the same as seen from below in FIG. 1;

FIG. 3 is a side elevational view of the same as seen from below in FIG. 2 showing the side opposite to that of FIG. 1;

FIG. 4 is an end view of the mirror end as seen from line 4—4 in FIG. 3;

FIG. 5 is an end view of the dental mouth mirror as seen from line 5—5 in FIG. 3;

FIG. 6 is a plan view taken along line 6—6 in FIG. 3 and parallel to the mirror;

FIG. 7 is a longitudinal section through that portion of the handle along line 7—7 in FIG. 6 and at larger scale with respect thereto;

FIG. 8 is an extension of the longitudinal section of FIG. 7 as taken along line 8—8 in FIG. 6;

FIG. 9 is a section through the mirror end only and taken along line 9—9 in FIG. 6;

FIG. 10 is a cross section through the handle taken along line 10—10 in FIG. 7;

FIG. 11 is a section through the handle as seen along line 11—11 in FIG. 7; and

FIG. 12 is an end view of the handle only as seen from line 12—12 in FIG. 7.

The characteristic feature of the design resides in the handle of the dental mouth mirror.

I claim:

The ornamental design for a dental mouth mirror, as shown and described.
